CLAIM

The ornamental design for a blender, as shown and described.

DESCRIPTION

FIG. 1 is a front and left side perspective view of a blender, showing my design.

FIG. 2 is a rear and right side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an exploded front and left side perspective view of the blender of FIG. 1; and,

FIG. 10 is an enlarged view of a portion of the blender labeled 10 in FIG. 1.

The broken lines in the drawings depict portions of the blender that form no part of the claimed design. The oblique line shading shown in the drawings indicates a transparent or translucent surface.
